UNITED STATES PATENT OFFICE.

GEORGE H. NAYLOR, OF TRENTON, NEW JERSEY, ASSIGNOR TO FRED R. PARKER, OF TRENTON, NEW JERSEY.

COLLAPSIBLE CORE.

1,133,445.

Specification of Letters Patent. Patented Mar. 30, 1915.

Application filed March 4, 1914. Serial No. 822,452.

To all whom it may concern:

Be it known that I, GEORGE H. NAYLOR, a citizen of the United States, residing at Trenton, in the county of Mercer and State of New Jersey, have invented certain new and useful Improvements in Collapsible Cores, of which the following is a specification, reference being had to the accompanying drawings.

10 This invention relates to new and useful improvements in cores for pneumatic tires and more particularly to that class of cores which are collapsible.

An object of this invention is the provision of a collapsible core which is composed of a plurality of segmental sections, the ends of the adjoining sections abutting against each other, the core being provided with means for connecting the several sections, 20 so that when connected, they form a circular member about which pneumatic tires may be molded.

A further object of this invention is the provision of improved means whereby the several segmental sections of the core may be quickly and easily connected to each other, and whereby the several sections may be quickly collapsed to remove the core from the tire after the same has been molded.

30 With these and other objects in view, my invention consists in the novel construction, arrangement, and combination of parts to be hereinafter more fully described, claimed, and illustrated in the accompanying drawings, in which—

Figure 1 is a side elevation, partly in section, of the core ready for use. Fig. 2 is an end view, partly in section, of one segment of the core. Fig. 3 is an end view 40 of another section of the core; and Fig. 4 is a fragmentary perspective view of one end of one of the segments.

Referring more particularly to the drawing, the numeral 5 designates a plurality 45 of segmental sections, which are annular in cross section, and which are preferably four in number as shown in the drawing. Each of the sections 5 is provided at its inner edge with a flange 6 which is substantially T-shaped in cross section, the enlarged head 7 of each flange being adapted 50 to project from the tire while the same is being molded upon the core. The opposite ends of each section 5 are adapted to abut 55 against the ends of the adjoining sections,

and each section is provided at one end thereof with a socket or recess 8, and at its opposite end with a projection or rib 9, the rib or projection 9 in each section being adapted for engagement in the recess 8 in the adjoining section so as to prevent outward separation of the several sections and arranged to form a core. The end of one section 5 is provided with a slot 10 at one end thereof which extends from the outer face of this section to the recess 8, so that the projection 9 on the adjoining section may slide through the slot 10 into the recess 8 and thereby allow the ends of the several sections to fit closely together. 70

Formed in the inner face of the enlarged head 7 of the flange of each section at its opposite ends, are slots 11, the slots in the adjoining sections registering to form recesses, to receive the locking plates 12. 75 Formed in the walls of each slot are a pair of registering tapered openings 12', the locking plates being also provided with openings 13 which register with the openings in the walls of the slots, and tapered pins 14 are adapted for engagement in the registering openings in the walls of the slots and the locking plates, to maintain the several sections in their respective positions, while the tire is being molded upon the core. 80 As the enlarged heads 7 of the flanges 6 project from the tire when the same is being molded, it will be seen that the pins 14 may be readily removed from the registering openings in the walls of the slots and the plates after the tire has been molded, so 85 that the plates 12 may be removed from the slots and the sections withdrawn from the molded tire. After the plates 12 have been removed from the slots, the end of the section 5 in which the slot 10 communicating with the recess 8 in the section is formed, may be moved inwardly, the slot 10 passing by the block 9 on the adjoining section, so 90 that the section having the slot 10 therein may be first withdrawn from the molded tire, the remaining sections 5 being capable of ready removal, after the first section is withdrawn.

The slot 11 in one end of each section is 105 preferably provided with a tapered inner wall 15, and one end of each locking plate 12 is provided with a notch or recess 16, so that a suitable tool (not shown) may be inserted in the notches 16 to easily remove 110

the locking plates 12 from the sections when the tapered pins 14 have been disengaged therefrom.

Having thus fully described my invention, 5 what I claim as new and desire to secure by Letters Patent is:

A collapsible core for tires comprising a plurality of segmental sections adapted to form a ring when the opposite ends of each 10 section are engaged against the ends of adjoining sections, each section being provided with a flange upon its inner edge to project from the tire while the same is being molded upon the core, the inner face 15 of each flange at its opposite ends being formed with slots, the slots of adjoining

sections registering when the core is in a position for use, the walls of said slots having tapered openings formed therein, locking plates having openings therein disposed 20 within the registering slots, said openings in the locking plates registering with the tapered openings in the walls of the slots, and tapered pins adapted for engagement through the registering openings to detach- 25 ably secure said plates in position.

In testimony whereof I hereunto affix my signature in the presence of two witnesses.

GEORGE H. NAYLOR.
